J. SYLVAN

WINDOW

Filed Aug. 18, 1920

Inventor

Joseph Sylvan

William C. Mekhops Atty

UNITED STATES PATENT OFFICE.

JOSEPH SYLVAN, OF CHICAGO, ILLINOIS, ASSIGNOR TO THE KINNEAR MANUFACTURING COMPANY, OF COLUMBUS, OHIO, A CORPORATION OF OHIO.

WINDOW.

Application filed August 18, 1920. Serial No. 404,365.

To all whom it may concern:

Be it known that I, JOSEPH SYLVAN, a citizen of the United States, and a resident of Chicago, in the county of Cook and State of Illinois, have invented certain new and useful Improvements in Windows; and I do hereby declare that the following is a full, clear, and exact description thereof, reference being had to the accompanying drawings, and to the letters of reference marked thereon, which form a part of this specification.

This invention relates to improvements in windows and consists of the matters hereinafter described and more particularly pointed out in the appended claims.

The primary object of the invention is to provide a window wherein both sash are so connected together that upon opening or closing of one sash a like movement is imparted to the other sash.

Another object of the invention is to so arrange the parts that when the window sash are in their open position the incoming air is deflected upwardly toward the ceiling of the room.

Other objects of the invention as well as the many advantages thereof will more fully appear as I proceed with my specification.

In the drawings—

Fig. 1 is a vertical section through a window embodying my invention with the sash in a closed position.

Fig. 2 is a similar section with the sash shown in an open position.

Figs. 3 and 4 are horizontal detail sectional views, on an enlarged scale, taken on the lines 3—3 and 4—4 respectively, of Fig. 1.

Referring now in detail to that embodiment of the invention illustrated in the accompanying drawings, 5 indicates a sheet metal window frame and 6 and 7 indicate the top and bottom window sash thereof respectively.

The window frame 5 comprises upright side members 8, a horizontal top member or lintel 9 and a horizontal bottom mem-

ber or sill 10. The side members 8 each have a centrally disposed, substantially wide web 11 which is spaced inwardly from the body part of each side member and is connected thereto, short of the margins 12, by flanges 13 to provide inwardly and outwardly opening grooves 14 and 15 respectively. At the top end of each web 11 of the side members 8 and preferably nearer the outer than the inner margins 12 thereof, is provided a vertically disposed slot 16, which is bound or defined on the inner surface of the web by a reinforcement 17. (See Fig. 3.)

The top member of the lintel 9 of the frame has a ledge 18 which depends from its outer margin, and in the bottom surface of said ledge is a downwardly opening groove 19. The sill 10 is provided on its top surface near its inner edge, with an upwardly and inwardly extending ridge or rib 20.

The top sash 6 is of the tubular sheet metal type and comprises top and bottom horizontal members 21—22 and upright side members 23, all of which are constructed to provide suitable channels to receive the pane 24.

The side members 23 of the top sash are spaced a short distance inwardly from the webs 11 of the frame and along the outer edge of said side members are hook flanges 25 which bridge and close the spaces 26 between said side members and webs. Said hook flanges normally engage in the outer grooves 15 (see Fig. 3) of the frame when the sash is in the closed position shown in Fig. 1. The top member 21 of the sash has inner and outer upright tongues 27—28 which act to form a tight joint at the top of the sash, the outer tongue normally engaging in the groove 19 in the ledge 18 for this purpose. The bottom member 22 of the sash is provided on its inner bottom marginal part with a groove 29 to receive a tongue on the top member of the bottom sash. In the hollow side members 23 of said upper sash, near their inner faces, are

secured upright flat bars 30 which extend through and beyond the top and bottom members 21—22 of the sash.

The bottom sash 7 comprises top and bottom horizontal members 31—32 and upright side members 33, all of which are hollow and are constructed to provide suitable channels to receive the pane 34. The side members 33 of the bottom sash are spaced a short distance inwardly from the webs 11 of the side members of the frame and along the inner edges of said side members are hook flanges 35 which bridge and close the spaces 26 between the said side members and webs 11 and normally engage in the inner grooves 14 when the sash is in its closed position as shown in Fig. 1. The top member 31 of the sash has a tongue 36 on its outer bottom edge adapted to extend into the groove 29 on the bottom member 22 of the top sash to form an airtight joint between them in the normal closed position. The top member 31 also has a handle 37 by which the sash is actuated and also on said top member and on the bottom member of the top sash are co-acting locking devices 38 to lock the window sash together. The bottom member 32 is formed to provide along its front bottom edge, a downwardly opening groove 39 which receives the rib 20 on the sill to provide a pivot or hinge between the said bottom sash and sill. In the hollow side members of the sash 7 near their outer faces are provided upright flat bars 40 which extend through and beyond the top and bottom members of said sash. Links 41 arranged in pairs connect the top ends of the bars 40 of the bottom window sash with the top ends of the bars 30 of the top window sash while similar links 42 arranged in pairs connect the bottom ends of the bars 40 with the bottom ends of the bars 30. Rivets or pins 43 provide the pivotal connection between the links and bars and spacing washers 44 are provided adjacent the connections to properly space the links from the sash as shown in Figs. 3 and 4. The rivets or pins 43 providing the pivotal connection between the top ends of the links 41 and the bars 30 are long enough to extend into the slots 16 in the webs 11 before mentioned.

The operation of the improved window is as follows:— Assume that the sash 6 and 7 are locked in the closed position shown in Fig. 1. The coacting locking devices 38 are actuated to unlock the sash and the operator grasps the handle 37 on the top member of the bottom sash and pulls the same inwardly and downwardly about the ribs 18 as a pivot. As the sash 7 thus swings, a vertically downward movement is imparted to the top end of the top sash owing to the guided movement of the pins 43 in the slots 16. As the top sash moves

downwardly its bottom end swings outwardly under the action of the links 42, the opening movement of the window sash being limited by the engagement of the pins 43 with the bottom ends of the slots 16. When the sash are in their open position the incoming air is deflected by both top and bottom sash, toward the ceiling of the room, a part of this air entering above the top of the top sash. Even should rain enter at this point it will fall upon the bottom sash to be directed outwardly by the slope or inclination thereof.

To close the windows, a push is imparted to the top edge of the bottom sash, which through the links 41 will lift the top end of the top sash and its bottom end will swing inwardly under the action of the links 42 so that both sash are again in the position shown in Fig. 1; after which they are locked together.

The improved window is especially adapted for use in factory and office buildings on account of the ventilation it affords. Both sash open and close together and when open afford a proper ventilation of the room and when closed prevents the entrance of drafts. As no expensive weights or sash cord connections need to be made, it is simple in construction and easy to install and remove for the purpose of painting and cleaning.

While in describing my invention I have referred to certain details of mechanical construction and arrangement of parts, I do not wish to be limited thereto except as may be pointed out in the appended claims.

I claim as my invention:

1. In combination with a window frame having slotted side members and a sill having a rib thereon, top and bottom sash in said frame, the bottom sash having a groove in its bottom member to receive said rib to provide a pivotal engagement for the bottom sash with said sill, links arranged in pairs and connecting the top and bottom ends of the sash together and pins providing the pivotal connection between said links and sash, the pins connecting the links with the top end of the top sash, extending into the slots in the side members of the frame.

2. In combination with a window frame having side members, top and bottom sash therein, brace bars fixed to the sides of the sash, and links arranged in pairs connecting the top ends and the bottom ends of both sash together, the bottom sash having a pivotal engagement with the sill of the frame and the top sash having a pin and slot connection with the side members of the frame.

3. In combination with a window frame having side members each including a central web part offset from the body part

thereof, each web part having oppositely facing inner and outer grooves, top and bottom sash having hooked flanges, engaging in said grooves when said sash are in their closed positions, and means connecting said sash together and operating upon the opening or closing movement of one sash to impart a like movement to the other sash.

In testimony that I claim the foregoing as my invention, I affix my signature in the ¹⁰ presence of two witnesses, this 12th day of August, A. D. 1920.

JOSEPH SYLVAN.
